UNITED STATES PATENT OFFICE.

CHARLES E. ANDERSON, OF LAPORTE, INDIANA.

ATTACHMENT FOR TRACTION-ENGINES.

SPECIFICATION forming part of Letters Patent No. 675,994, dated June 11, 1901.

Application filed February 27, 1901. Serial No. 49,109. (No model.)

To all whom it may concern:

Be it known that I, CHARLES E. ANDERSON, a citizen of the United States, residing at La-
porte, in the county of Laporte and State of
5 Indiana, have invented a new and useful At-
tachment for Traction-Engines, of which the
following is a specification.

This invention relates to traction-engines;
and it has for its object to provide a cheap
10 and simple tender and means for connecting
it with the boiler of the engine in such man-
ner as to permit of free movement of the ten-
der to conform to uneven portions of the road.

A further object of the invention is to pro-
15 vide a construction wherein the body of the
tender will at all times directly follow the en-
gine, the axle of the tender being turned to
guide the tender.

Other objects and advantages of the inven-
20 tion will be apparent from the following de-
scription.

In the drawings forming a portion of this
specification, and in which like numerals of
reference indicate similar parts in the several
25 views, Figure 1 is a bottom plan view of a
traction-engine equipped in accordance with
the present invention. Fig. 2 is a side eleva-
tion of the engine with its tender. Fig. 3
is a transverse section through the tender and
30 showing the guides for the draw-bar. Fig. 4
is a detail horizontal section through a por-
tion of the tender-axle and showing the con-
nection of the draw-bar which connects the
tender with the engine. Fig. 5 is a detail sec-
35 tion through a portion of the bottom of the
tender and showing the connection of the wa-
ter-feed pipe therewith. Fig. 6 is a perspec-
tive view showing the connection between the
forward portion of the tender and the draw-
40 bar through which the threshing-machine is
connected with the engine. Fig. 7 is a detail
perspective view of the bracket to which the
tender draw-bar is attached.

Referring now to the drawings, there is
45 shown a traction-engine comprising a boiler
10, having the forward steering-wheels 11,
mounted at the ends of a pivoted axle 12, to
which are attached the ends of a chain 13, the
central portion of which is wound upon a drum
50 14, mounted upon the under side of the boiler.
The drum is provided with a sprocket 15, and
engaged therewith is a worm 16, having an
operating-shaft 17. When the worm is ro-
tated one way or the other, the drum is cor-
respondingly rotated to wind up either end 55
portion of the chain and correspondingly
move the front axle.

The engine is provided with a drive-axle 17,
provided with traction-wheels 18, which are
operated in the usual manner.

In connection with the engine there is em-
ployed a tender which includes a body por-
tion 19, which may be rectangular, as shown,
and includes a water-tank 20, above which
are outwardly and upwardly flaring sides 22 65
and 23, which act to hold the fuel which is
carried upon the top of the water-tank.

The body of the tender is provided with a
transverse bolster 24, which is disposed
slightly in the rear of the center of the body,
so that the forward end of the tender will
have a tendency to tilt downwardly, and with
this bolster is engaged a king-bolt 24', which
is passed through the axle 25 of the tender
to permit of pivotal movement of the latter,
75 and this axle is provided with supporting-
wheels 26. A plate 27 is secured to the front
face of the axle and has vertically-spaced ears
28, having alining perforations with which
is engaged a pivot-bolt 29, which engages the 80
eye 30 at the bight of a draw-bar, formed by
bending a rod 30 upon itself, the diverging
end portions 31 and 32 of the rod being pro-
vided with eyes 33, which are engaged with
hooks or eyes 33' upon the sill 34 at the rear 85.
end of the platform of the cab of the engine.
The axle is thus held against bodily move-
ment toward or away from the engine, while
it may have free pivotal movement to permit
the tender to be readily drawn around curves. 90
The lower end of the king-bolt 24' is passed
through the bight of a yoke-plate 35, having
bolts 36 and 37 passed transversely through
the legs thereof and spaced vertically, and
between these bolts, which form guides, is 95
passed the stem of a draw-bar 38, having an
eye 39, through which is passed a pin 40, en-
gaged with perforations in vertically-spaced
plates 41 and 42, secured to the under side of
the fire-box of the boiler. This draw-bar is 100
intended for connection with the threshing-
machine, and the strain exerted by said ma-
chine is thus applied directly to the boiler.

Ears 43 and 44 are secured to the under

- side of the tender adjacent to the front end thereof and have transversely-alining perforations adapted for engagement interchangeably by a pivot-pin 45, which is passed through 5 a U-shaped rocker 46, the ends of which are provided with clips 46, through which the draw-bar is passed. The front end of the tender is thus prevented from tilting in either direction to an excessive degree, while there 10 is that freedom of movement between the engine and tender which permits of both running smoothly and conforming individually to the uneven portions of a road. The rear end of the bar 38 has an eye to facilitate connection with a threshing-machine, and brace-bars 47 are connected with the lower bolt 37 and are disposed to diverge upwardly and have their upper ends secured to the under side of the body of the tender.
- 20 In order that the axle of the tender may be turned with the front axle of the engine, rods and chains 48 and 49 are attached to hooks or eyebolts at the ends of the axle of the tender, said rods and chains passing forwardly 25 and the chains being engaged over rollers 50 and 51, after which they are crossed and attached to opposite ends of the front axle of the engine.
- 25 The guide-rollers may of course be placed 30 wherever desired to secure the most efficient results, and the rods are provided with turn-buckles, as shown, so that they may be adjusted to place the chains under proper tension.
- 35 To indicate the height of water in the tank of the tender, a gage-glass 51 is secured to one side thereof, and to draw water from the tank a feed-pipe or suction-pipe 53 is connected thereto. An opening 54 is formed in 40 the bottom of the tank and against the under side of the tank, and closing the opening is a concaved plate 55, seated upon a gasket 56 and held in place by bolts 57. Centrally of

this plate is a screw-threaded perforation, with which is engaged the suction-pipe referred to. 45

What is claimed is—

1. The combination with a traction-engine including a boiler and supporting-wheels, of a tender having an axle pivoted thereto, means for holding the body of the tender in alignment with the body of the boiler, means for turning the axle from the boiler, and a draw-bar comprising diverging arms pivoted at their inner ends to the axle in advance of and adjacent to the pivot of the axle, and pivoted 50 at their outer ends to the boiler, whereby the draw will be directly upon the axle and pivotal movement of the axle will be permitted. 55

2. The combination with a traction-engine including a boiler and supporting-wheels, a 60 tender having a pivoted axle, a draw-bar pivoted to the engine for movement in a vertical plane only and pivoted to the axle of the tender to permit of pivotal movement thereof, a draw-bar connected with the engine and 65 passed beneath the tender and the axle thereof, means for holding said bar against downward movement from the tender, and connections between said bar and the body of the tender to prevent tilting of the latter. 70

3. The combination with a locomotive having a draw-bar connected therewith, of a tender connected with the locomotive and beneath which said draw-bar is passed, an axle for the tender having supporting-wheels and 75 below which the draw-bar is disposed, and a rocker pivotally mounted upon the underside of the tender forward of its axle and with which the draw-bar is slidably engaged.

In testimony that I claim the foregoing as 80 my own I have hereto affixed my signature in the presence of two witnesses.

CHARLES E. ANDERSON.
